COLLAPSIBLE MULTIPLE PURPOSE
FURNITURE

Edward P. La Kaff, Chicago, Ill.

Application November 15, 1950, Serial No. 195,820

4 Claims. (Cl. 5—82)

1

This invention relates to collapsible furniture having a plurality of functions.

Specifically this invention relates to a combination foldable cot, stretcher, and litter.

The invention will be hereinafter specifically described as embodied in a collapsible cot having swinging legs adapted to serve as handles to convert the cot into a stretcher or to permit the cot to rest flat on the ground. It should be understood, however, that the principles of this invention are generally applicable to collapsible furniture and the invention is therefore not to be limited to the herein disclosed preferred embodiment.

According to this invention, a pair of pivoted together metal tubes, of generally U shape, have end portions each rotatably carrying a generally L-shaped tube with one leg of the L extending therein and the other leg forming a cot supporting leg or a stretcher handle. The two legs of the tube are joined through a rounded knee on which the frame tubes rest when the device is opened up in cot form. The pair of metal tubes forming the main frame each have an elongated side leg between the pivoted together end legs thereof and these elongated side legs receive therearound tubular sheeting material such as a canvas band to form the bed portion of the cot or stretcher. The pivoted together pair of metal tubes have their side legs in staggered relation so that the side leg of one tube lies outside the adjacent side leg of the other tube at one end of the cot and inside the adjacent leg of the other tube at the other end of the cot.

The L-shaped tubes which are rotatably mounted in the ends of the main frame pieces are equipped with retaining means which will maintain them in desired upright cot supporting position, outturned stretcher handle forming position, or inturned stacking position.

It is, then, an object of this invention to provide collapsible furniture composed of pivoted together frame members each carrying swingable end members adapted to form legs or handles.

Another object of the invention is to provide a combination field cot and stretcher wherein pivoted together main frame members have swivelly mounted legs in the ends thereof which are positioned to form stretcher handles or cot supporting legs.

Another object of the invention is to provide a collapsible cot with swivelly mounted legs having knee portions supporting the cot.

2

Another object of the invention is to provide a collapsible cot with swingable legs having pin and socket connection with the cot frame and equipped with knee portions receiving the load of the cot and effective to wedge the pin and slot connections together under the loaded cot.

Other and further objects of the invention will be apparent to those skilled in the art from the following detailed description of the annexed sheets which, by way of a preferred example only, illustrate one embodiment of the invention.

On the drawings:

Figure 1 is a perspective view showing the device of this invention opened up for use as a cot and having part of the supporting surface thereof broken away to show underlying frame structure.

Figure 2 is a plan view of the cot of Figure 1 also having parts broken away to show underlying frame structure.

Figure 3 is a view similar to Figure 2 but showing the legs of the cot swung outwardly to provide stretcher handles.

Figure 4 is an end view of the cot of Figure 2.

Figure 5 is a broken plan view of the cot in collapsed position for vertical stacking.

Figure 6 is an end view of the collapsed cot shown in Figure 5.

Figure 7 is a sectional view taken along the line VII—VII of Figure 5 but illustrating the legs swung inwardly for stacking purposes.

Figure 8 is an enlarged fragmentary vertical cross-sectional view, with parts in elevation, taken along the line VIII—VIII of Figure 2.

Figure 9 is a transverse cross-sectional view, with parts in elevation, taken along the line IX—IX of Figure 8.

As shown on the drawings:

As shown in Figure 1, the cot 10 of this invention is composed of two generally U-shaped tubular metal frames 11 and 12, a tubular or endless band 13 of canvas or the like, pivot studs 14, 14 connecting the frames 11 and 12, and four separate legs 15 swivelly mounted in the ends of the frames 11 and 12.

As best shown in Figure 2, the frame 11 has an elongated side leg 11a and end legs 11b, 11b extending at right angles from the ends of the side leg. The frame 12 has an identical side leg 12a and end legs 12b, 12b. The side legs 11a and 12a receive the band 13 therearound and this band terminates in closely spaced relation to the end legs.

One end leg 11b of the frame 11 lies inside of

the adjacent leg 12b of the frame 12 at one end of the cot while at the other end of the cot the leg 11b lies outside of the adjacent leg 12b. The frame pieces 11 and 12 are thus in staggered relation.

As best shown in the end view of Figure 4, the end legs 11b and 12b are kinked or offset adjacent the pivot stud 14 so that the side leg 11a may rest on the supporting leg 15 carried by the frame 12 and so that the side leg 12a may rest on the supporting leg 15 carried by the frame 11.

As best shown in Figure 2, each end leg of each frame has an inwardly extending portion. Thus the legs 11b have inwardly extending portions 11c, while the legs 12b have inwardly extending portions 12c. These portions 11c and 12c lie in the same plane as the legs from which they extend and have collars 16 secured on their ends. These collars, as best shown in Figures 8 and 9, have vertical notches 16a and horizontal notches 16b in their end faces, for a purpose to be hereinafter described.

The cot supporting legs 15 are generally L-shaped, having legs 15a slidably and rotatably receivable in the end portions 11c and 12c of the frame pieces. These legs 15a extend outwardly from the frame pieces to rounded knee portions 15b. The knees 15b merge into leg portions 15c in obtuse angular relation with the legs 15a.

As shown in Figure 8, the leg portions 15a have an open ended tube 17 extending therethrough in spaced relation from the knee 15b. A spring 18 is anchored at one end on this tube 17. The other end of the spring is anchored on a pin 19 secured in the end portion 11c or 12c receiving the leg. A pin 20 is mounted in the tube 17 and projects beyond both ends of the tube through notches 21 in the end 12c or 11c of the frame piece aligned with the notches 16a and 16b of the collar. The pin 20 has heads 22 on the ends thereof seatable in these notches. The tube and pin arrangement makes possible easy mounting of the legs 15 in the frame pieces, since the spring 18 can be mounted on the tube 17, the leg piece can be inserted into the frame 11c or 12c to align the other end of the spring with holes in the frame and pin 19 can then be dropped through these holes and through the end of the spring. The leg 15 can next be pulled outwardly from the frame piece to stretch the spring 18 until the ends of the tube 17 are exposed beyond the frame piece whereupon the pin 20 can be passed through the tube, the heads 22 affixed thereon, and the assembly released to allow the spring 18 to seat the pin heads against the collar 16 in either the notches 16a or 16b thereof.

When the unit 10 is to be used as a cot as shown in Figures 1 and 2, the legs 15 are rotated so that the heads 22 of the pin 20 are seated in the vertical notches 16a of the collars 16. In this position, the knees 15b of the legs will be under the adjacent side legs 11a or 12a of the frame and the leg portions 15c will extend downwardly to hold the sheet material 13 above ground level. As shown in Figure 4, in this position the knees 15c are loaded by the legs 11a and 12a of the frame and tend to force the leg portions 15a into the end portions of the frames 11c or 12c whereupon the heads 22 of the pins 20 will be wedged into the notches 16a.

When it is desired to use the cot 10 as a stretcher or litter, the legs 15 are swung to the positions shown in Figure 3. In these positions of the legs, the heads 22 of the pins 20 are seated

in the horizontal notches 16b of the collars and do not show in the plan view of Figure 3. The leg portions 15c extend outwardly from the side legs 11a and 12a of the frame pieces to provide easily accessible handles. The spring 18 will be effective to hold the heads of the pins in the horizontal notches so that the handle portions 15c cannot swing.

In order to move the legs 15 from cot supporting position to stretcher handle position, or to an inwardly collapsed position as shown in Figure 7, it is only necessary to pull the legs slightly outwardly from their supporting frames against the load of the springs 18 to detach the pin heads 22 from the notches in which they are seated and to then rotate the legs to the desired position permitting the spring to snap the pin heads into the notches for holding the legs in the new position.

As shown in Figures 5 and 6, the cot 10 can be easily folded into a collapsed condition and stacked upright on the legs 15 by merely swinging the frame pieces 11 and 12 so that their side legs 11a and 12a are brought together as shown. In this collapsed position, the looped band 13 hangs loosely from the side legs and can be easily removed over the end legs if it is desired to replace the band. As illustrated in Figure 6, the legs 15 will hold the cot in a collapsed position for stacking purposes.

As shown in Figure 7, if it is desired to pack the collapsed cot in a very small space, the legs 15 can be swung to the position shown inwardly from the end legs which carry them.

From the above descriptions it will therefore be understood that this invention now provides collapsible furniture having a plurality of functions. The preferred embodiment of the invention deals with a collapsible cot that has swivelly mounted legs for supporting the cot from the ground or for forming handles so that the cot may be used as a field stretcher.

It will be understood that modifications and variations may be effected without departing from the scope of the novel concepts of the present invention.

I claim as my invention:

1. A combination cot and stretcher comprising a frame having side portions, pivoted together end legs on said side portions, and inwardly directed portions on the ends of the end legs, L-shaped leg members swivelly mounted in said inwardly directed portions and having knees adapted to engage the side portions, and means for selectively locking said leg members in cot leg positions and in stretcher handle positions.

2. A collapsible combination cot and stretcher which comprises a pair of tubular metal U-shaped frames each having a bight portion with end legs extending in the same direction at right angles to said bight portion and inwardly directed end portions on the end legs, said frames being connected together and operable to an opened up position with said bight portions in generally parallel spaced relation together defining a support, an angle member mounted on each inwardly directed portion and having one leg thereof telescoped in said portion with the other leg thereof extending at an angle therefrom and joined with the first mentioned leg through a rounded knee, said knee being positioned to extend under one of said bight portions of the frame when the cot is in said opened up position whereupon said bight portions will exert an inwardly directed force on the other legs and said

other legs being adapted to be swung from cot leg defining positions to outwardly extending handle positions beyond said bight portions of the frame.

3. A furniture article comprising: a pair of tubular generally U-shaped frames having generally parallel bight portions together defining a support and having end leg portions pivotally connected for relative pivotal movement of said frames about an axis generally parallel to and equally spaced from said bight portions, and L-shaped members each having one leg telescoping with and swivelly secured to the extremity of one of said tubular end leg portions, and means for selectively locking said one leg of each L-shaped member in selected non-swivelling positions relative to the associated end leg portion of said frames to position the other leg of each L-shaped member downwardly, outwardly, or inwardly relative to said frames, said one leg of each L-shaped member being disposed in the path of the bight portion of the other frame to provide support therefor.

4. A collapsible article of furniture which comprises a pair of generally U-shaped frames each having an elongated bight portion and end leg portions fixed generally at right angles thereto, the frames being disposed in straddled relation with one end leg of one frame outside and adjacent one end leg of the other frame, and with the other end leg of said one frame inside and adjacent the other end leg of said other frame, a pivot connecting said one end legs and a pivot connecting said other end legs for relative pivotal movement of said frames about said

pivots, a first inwardly directed end portion on said one outside end leg of said one frame and a second inwardly directed end portion on said other outside end leg of said other frame, said one frame having a first portion connected to said first inwardly directed end portion engaging and supporting the bight portion of said other frame and a second portion connected to said first portion and extending angularly to said first portion providing a support leg, said other frame having a third portion connected to said second inwardly directed end portion engaging and supporting the bight portion of said one frame and a fourth portion connected to said third portion and extending angularly thereto to provide a support leg, and further portions connected respectively to said inside other leg portion of said one frame and said inside one leg portion of said other frame for providing additional support for said frame.
